UNITED STATES PATENT OFFICE.

FERDINAND KULHAWY, OF PHILADELPHIA, PENNSYLVANIA.

REVOLVING-HOOK MECHANISM.

1,152,740.

Specification of Letters Patent.

Patented Sept. 7, 1915.

Application filed October 21, 1914. Serial No. 867,778.

To all whom it may concern:

Be it known that I, FERDINAND KULHAWY, a subject of the Czar of Russia, residing at Philadelphia, in the county of Philadelphia and State of Pennsylvania, have invented certain new and useful Improvements in Revolving-Hook Mechanism, of which the following is a specification.

This invention relates to certain new and useful improvements in revolving hook mechanism.

An object of the present invention is to provide a bobbin case support and bobbin case for sewing machines in which the bobbin case *per se* is particularly constructed to carry a greater amount of thread, and to be used with the usual operating mechanism.

A further object of the invention is to provide a revolving hook mechanism in which the bobbin case carried by a suitable support is formed with a guide against which abuts an arm of the thread looping mechanism to positively guide the thread to form a loop and obviate a break in the stitching or knotting of the thread.

Other objects of the invention will appear as the nature of the same is better understood, and the device consists in the novel construction, combination and arrangement of parts to be hereinafter more fully described, and then claimed.

In the accompanying drawing forming a part of this application and to which reference is had herein by like characters designating corresponding parts throughout the several views, Figure 1 is an end elevational view of the bobbin case and support therefor. Fig. 2 is a side elevational view of the same. Fig. 3 is a horizontal sectional view of the same. Fig. 4 is a longitudinal sectional view. Fig. 5 is a modification of the device showing the bobbin case in use with a continuous rotating thread looper. Fig. 6 is a front elevational view of the bobbin case. Fig. 7 is a vertical longitudinal sectional view of the same. Fig. 8 is a detail perspective view of the thread spool, and Fig. 9 is a detail perspective view of one of the bobbin case clamping arms.

Briefly described, the improvement consists in providing a sewing machine bobbin case and operating mechanism therefor in which the bobbin case is constructed with a view of containing a larger amount of thread, and in which the same is held positioned within the support therefor by par-

ticular clamping means. The bobbin case is provided with an extension on one side thereof, in the form of a substantially semi-circular guide or track over which the revolving arm of the revolving hook mechanism is adapted to travel, and be in continuous contact therewith for the major portion of its movement to insure a positive separation of the looped thread, in order to position the same about the thread issuing from the bobbin case.

My invention is equally applicable to mechanism on an oscillatory or continuously rotated revolving hook mechanism, which will appear in the following detail description.

Referring more in detail to the accompanying drawing, the reference numeral 10 designates the support or body portion of the revolving hook mechanism and is provided with a lateral extension 11 beneath which, as clearly indicated in Fig. 4 the bobbin case and supporting mechanism are suspended. The bobbin case supporting mechanism consists of a pair of arms 12 and 13 suitably shaped as shown in detail in Fig. 9 with the arm 12 formed substantially rigid with the extension 11, while the arm 13 is provided with a detent enlargement 14 at the upper end thereof and by which the said arm 13 is pivoted to the extension 11 as indicated at 15 in Figs. 2 and 4. A finger grip 13' is carried by the arm 13 and affords means for moving the said arm on its pivot 15. The bobbin case 16 is positioned between the arms 12 and 13, and has a slight relative movement thereto, so that the thread being looped, in a manner to be hereinafter described, will be permitted to pass between the arms 12 and 13 and the bobbin case 16. A flat spring 17 is connected at one end to the body support 10 and engages at its free end the enlarged head or shoulder 14 to hold the same in open or closed position as shown by full and dotted lines in Fig. 4. Lugs 16' are carried by the bobbin case to be engaged by the arms 12 and 13 to add rigidity to the device, and limit the movement of the bobbin case in one direction, the said bobbin case being limited in its movement in the opposite direction by the lips 14'. 100

The bobbin case 16 comprises the usual shell device consisting of a socket or spool holder portion 18 of increased size and closed at its outer end by the spring pressed hinged cap plate 19. The thread spool 20

shown in Fig. 8 is provided axially of the end disks with projecting pins 21 to be received in sockets 22 formed in the bottom of the socket 18 and in the central portion of the cover cap 19. The face of the bobbin case is provided with a thread guide slot 23 through which the thread is led to the terminal opening 24 from which the thread is fed to the revolving hook mechanism. Pivoted to the same face of the bobbin case 16 is a resilient spring plate 25, the particular design of which is shown more clearly in Fig. 6, with the free end thereof bent inwardly to spring into a small opening provided in the front face of the bobbin case, it being the object of this plate to tension the thread passing through the opening 24. The opposite face of the bobbin case 16 is provided with a substantially semi-circular 20 guide or track 26 over which the thread revolving arm is adapted to pass.

The operating mechanism for the bobbin case support and looper arm embodies a shaft 27 journaled in the support 10 as indicated in Figs. 3 and 4, and has the operating end thereof provided with an angularly bent arm 28 carrying on its outer end the thread revolving head 29. The revolving head 29 consists of a bifurcated or forked member 30 with an angular base wall 30, and of outer and inner furcations 31 and 32 respectively, so that the thread to be looped as indicated at "a" in Fig. 1, and the angular base wall 30 insures a separation of the thread when 35 the revolving head 29 passes over the guide track 26.

The shaft 27 is oscillated, and imparts a similar movement to the revolving head 29 during which movement, the looper head 29 40 engages the loop thread "a" fed downwardly from the upper face of the machine and passes over the guide track 26 in such position as to separate the loop thread "a" so that each strand of the loop will be positioned 45 on opposite sides of the bobbin case and pass between the bobbin case supporting arms 12 and 13 and the bobbin case 16. When the looper head 29 reaches the dotted line position shown in Fig. 1, the loop thread "a" 50 will be permitted to escape from the looper head, and by being drawn outwardly will pass about the single thread "b" issuing

from the bobbin case spool 20 to thereby form a loop. In its travel over the guide track 26, the looper head 29 is in continuous contact therewith for the major portion of the length of its travel so that the thread "a" will be positively separated or divided over the bobbin case. 55

A modification of the invention is shown 60 in Fig. 5, and in this instance the construction discloses a continuously rotatable revolving hook mechanism. The support 10 carries an arm 33 provided with a supporting member 34 on which is mounted the bobbin case 16. The shaft 27, angular extensions 28 and looper head 29 are identical in structure to the parts before described, and are continuously rotated, to catch the upper thread "a" to loop the same and form a tie 70 with the thread "b."

While the forms of the invention herein shown and described are what are believed to be the preferred embodiments thereof, minor changes may be made therein without 75 departing from the spirit and scope of the invention as set forth in the claim.

What I claim as new is:

The combination with a substantially L-shaped head having an opening therethrough, of an oscillatory shaft passing through said opening, a bobbin case support pivoted to the head and arranged to swing in and out of the angle of the L-shaped head, the bobbin case support being provided with an end adjacent its pivot point constituting a detent, a spring carried by the head and arranged to lock the bobbin case support in selected positions, the bobbin case support being provided with a pair of broad and flat arms of resilient material having opposed converging sides, in combination with a bobbin case having converging sides terminating in a guide rib, the bobbin case being adapted to be locked in 95 the arms in one position only and a revolving hook carried by said shaft and oscillatable over the guide rib. 85

In testimony whereof I affix my signature in presence of two witnesses.

FERDINAND KULHAWY.
